X-RAY TUBE

Zed J. Atlee, Elmhurst, Ill., assignor to General Electric X-Ray Corporation, Chicago, Ill., a corporation of New York

Application May 5, 1941, Serial No. 391,947

11 Claims. (Cl. 256—86)

My invention relates in general to electronics and has more particular reference to the provision of an improved X-ray generator.

An important object of the present invention is to provide an X-ray generator having an envelope structure substantially immune to deterioration as a result of X-ray and electronic action; a further object being to provide an X-ray tube in which all portions of the envelope normally exposed to X-ray and electronic action during operation of the tube comprise metal substantially immune to deterioration; a still further object being to utilize a metal tube as an envelope in an X-ray generator.

Another important object is to prevent metallic deposit, caused on the envelope by electrode deterioration during operation of the generator, from impairing the substantial transparency of the envelope to X-rays; a further object being to provide the envelope with a screen member shiftable progressively to present portions free of metallic deposit in position to transmit useful X-rays through the envelope; a still further object being to provide a windowed guard and co-operating screen in the generator, the screen being movable in said window to enable deposit-free screen portions to be progressively presented at said window in order to maintain X-ray transparency of the window structure.

These and numerous other important objects, advantages, and inherent functions of the invention will become apparent as the invention is more fully understood from the following description, which, taken in conjunction with the accompanying drawing, discloses a preferred embodiment of the invention.

Referring to the drawing:

Figure 1 is a sectional view through an X-ray generator embodying the present invention; and

Figure 2 is a sectional view taken substantially along the line 2—2 in Figure 1.

To illustrate the invention, I have shown on the drawing an X-ray tube 11 comprising an anode 13 and a cathode 15 enclosed in a sealed envelope preferably comprising a seamless steel tube 17.

The anode 13 comprises a head supporting a target 19 opposite the cathode in position to receive the impingement of electrons emitted by the cathode during the operation of the device as an X-ray generator. The cathode also comprises a head in which may be mounted a filamentary element 21 adapted to be energized to form a source of electrons for impingement upon the anode target 19. The heads of the anode

5 and cathode are supported on stems 23 at the opposite ends of the generator, said stems 23 each being supported in an end seal structure forming an hermetic seal between the stem and the ends of the envelope member 17. To this end, each stem 23 is formed with a seat 25, and each stem carries a cup-shaped metallic seal element 29 formed with an opening at one end to snugly receive the stem on which mounted, the members 29 being hermetically sealed each on its carrying stem at the seat 25. Each member 29 extends from its seat 25 and forms a skirt embracing the stem on which it is mounted and forms an annular edge making a glass-to-metal seal 31 with a co-operating glass end seal member 33. Each seal member 33 comprises a glass disk having a central neck forming the seal 31 and a marginal flange forming a glass-to-metal seal 35 with one end of a rim 37, the other end of which is hermetically sealed on an annular ring member 39. The anode and cathode electrodes are thus each supported on a ring member 39, which ring members are sealed to the opposite ends of the envelope member 17 preferably by means of silver soldered joints 41.

10 X-rays generated at the anode are emitted radially thereof generally in the direction of the inclination at which the target is mounted, useful rays passing outwardly of the envelope opposite the end of the anode electrode. If desired, the preferably steel envelope 17 may be formed with a window opening 43 opposite the target 19, and a pane of material 45, which is substantially transparent to X-rays, may be sealed on the envelope at said opening. I prefer to utilize a beryllium window-pane 45 for this purpose, since beryllium is substantially transparent to X-rays. The beryllium window-pane may be applied by soldering it in a ring of cold rolled steel 47 by means of a suitable solder 49, which may comprise an alloy of silver and copper in substantially equal quantities of each, the preferably steel ring 47 being brazed, soldered or welded to the steel tube 17 in any suitable or preferred vacuum-tight fashion.

15 It should be understood that X-ray generators function to produce X-rays in response to the activation of the anode by electronic action established by the operation of the cathode, said electronic action consisting of the impingement of electrons emitted by the cathode upon the anode target 19. Electronic impingement on the target results in the generation of relatively large quantities of heat at the target, which is dissipated thence through the body of the an-

ode and the anode stem 23, which may carry heat dissipating means thereon outwardly of the envelope. Heat generated at the cathode likewise may be dissipated thence through the cathode stem which extends outwardly of the envelope through the end seal. When the device is in operation, however, the temperature at the anode may be of the order of 500° centigrade and over, approaching the melting temperature of the target material. Electronic action on the target at operating temperature results in the evaporation of the material of the target, and the material of the cathode and its filament may also be gradually dissipated by evaporation during the operating life of the generator. The metallic material of the anode and cathode, thus vaporized and dissipated during operation, becomes deposited upon the interior surfaces of the envelope, particularly in the zone radially of the facing ends of the electrodes. In course of time during the operation of the device, the film thus deposited may build up to sufficient thickness to appreciably impair the X-ray transparency of the envelope, and particularly of the window 45, and thus impair the efficiency of the device as a source of useful X-rays.

In order to maintain the efficiency of the generator as a source of useful X-rays, I propose means for eliminating the deleterious effects of metallic deposit, and to this end I provide, within the envelope 17, an annular sleeve or shield 51 disposed within the envelope member 17, said shield 51 comprising preferably a steel tube of a size to fit within the tubular member 17 and provided with a rim 53 at one end of the tube 51, by means of which it may be secured, as by spot welding or otherwise, to and within the member 17 in position embracing the facing ends of the electrodes 13 and 15. The tube 51 is provided with an opening 55 in line with the X-ray translucent envelope portion 45.

It will be noted that the sleeve 51 defines an annular channel with the envelope 17 outwardly of the shield 51, and within this annular channel, I dispose a preferably cylindrical shutter 57 of any suitable material which is substantially transparent to X-rays. The shutter 57 conveniently may be formed of aluminum which, in addition to being substantially transparent to X-rays, is light in weight. As the generator is operated in service, the inner surfaces of the screen 51 will receive the metallic deposit resulting from vaporization of the electrode materials but will screen the shutter 57 against metallic deposit thereon, except at the shutter portions exposed in the opening 55. After such exposed portions, however, have received a metallic deposit to a thickness materially impairing the efficiency of the device as a source of effective X-rays passing through the window 45, the shutter 57 may be turned in order to present an uncoated portion thereof at the opening 55, thereby completely restoring the efficiency of the generator as a source of X-rays delivered through the opening 55 and the window 45.

Any suitable means may be employed for turning the shutter 57, and I have shown a magnetic vane 59 comprising a bar of suitable magnetic material secured at the edge of the shutter in position to be actuated by a magnet operated externally of the envelope. The operating magnet may simply be a magnetic body applied outwardly of the shell 17 opposite the vane 59 and then shifted circumferentially of the shell 17

through a distance sufficient to move the shutter into position presenting a fresh shutter surface, uncoated by metallic deposit, in the opening 55. Alternately and preferably, the external shutter-operating magnet may be applied, as shown at 61, within a chamber 63 formed in the end of the generator by the anode-supporting end seal, the wall of this chamber, defined by the glass seal member 33, being disposed closely adjacent the magnetic vane 59 and separated therefrom by the non-magnetic glass material of the end seal member 33.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. A device of the class described, comprising an envelope, electrode means within said envelope, overlapping shield and shutter means within said envelope in position to receive material vaporized as a result of the actuation of the electrode means, said shield means being formed with an opening and being disposed between said shutter means and said electrode means, whereby to uncover a portion of the shutter means at said opening, said shield and shutter means being relatively movable to present remote portions of the shutter means in position to receive said vaporized material at said opening.

2. A device of the class described, comprising an envelope, electrode means within said envelope, overlapping shield and shutter means within said envelope in position to receive material vaporized as a result of the actuation of the electrode means, said shield means being formed with an opening and being disposed between said shutter means and said electrode means, whereby to uncover a portion of the shutter means at said opening, said shield and shutter means being relatively movable to present remote portions of the shutter means in position to receive said vaporized material at said opening, and magnetic means for relatively moving said shield and shutter means.

3. A device of the class described, comprising an envelope, electrode means within said envelope, overlapping shield and shutter means within said envelope in position to receive material vaporized as a result of the actuation of the electrode means, said shield means being formed with an opening and being disposed between said shutter means and said electrode means, whereby to uncover a portion of the shutter means at said opening, said shield and shutter means being relatively movable to present remote portions of the shutter means in position to receive said vaporized material at said opening, and magnetic means, controllable from a position outwardly of said envelope, for relatively moving said shield and shutter means.

4. A device of the class described, comprising an envelope, electrode means within said envelope, concentrically disposed shield and shutter means within said envelope in position encircling the electrode means, said shield means being formed with an opening and being disposed between said shutter means and said elec-

trode means, whereby to uncover a portion of the shutter means at said opening, said shield and shutter means being relatively turnable, the one with respect to the other, in order to present remote portions of the shutter means in exposed position at said opening.

5. A device of the class described, comprising an envelope, electrode means within said envelope, an annular shield within said envelope and formed with a window opposite said electrode means, and a cylindrical shutter encircling said shield within said envelope, said shutter being turnable with respect to said shield whereby to present remote portions of the shutter in position exposed at said window.

6. A device of the class described, comprising electrode means, means forming an envelope enclosing the electrode means and providing a shield formed with an opening opposite said electrode means and a movable shutter co-operatively associated with said shield and operable to present remote portions of said shutter in said opening.

7. A device of the class described, comprising an envelope, electrode means within said envelope and including an anode adapted to be energized to constitute a source of X-rays, a shield in said envelope adjacent said anode, said shield being formed with an opening in the path of useful X-rays emanating from said anode, and a shutter of material substantially transparent to X-rays disposed in said envelope outwardly of said shield, said shield and shutter being relatively movable to present remote portions of the shutter in position exposed at said opening.

8. A device of the class described, comprising an envelope, said envelope comprising a tubular metallic member and end seals on said member, electrode means in said envelope and supported on said end seals, means on said envelope forming a shield spaced from and having an opening opposite said electrode means, and a shutter on the side of said shield remote from said elec-

trode means and movable with respect to the shield to present remote portions of the shutter at said opening.

9. A device of the class described, comprising an envelope, said envelope comprising a tubular metallic member and end seals on said member, electrode means in said envelope and supported on said end seals, means on said envelope forming a shield spaced from and having an opening opposite said electrode means, and a shutter on the side of said shield remote from said electrode means and movable with respect to the shield to present remote portions of the shutter at said opening, said shutter comprising material substantially transparent to X-rays.

10. A device of the class described, comprising an envelope, said envelope comprising a tubular metallic member and end seals on said member, electrode means in said envelope and supported on said end seals, means on said envelope forming a shield spaced from and having an opening opposite said electrode means, and a shutter on the side of said shield remote from said electrode means and movable with respect to the shield to present remote portions of the shutter at said opening, said shutter comprising aluminum.

11. A device of the class described, comprising an envelope, said envelope comprising a tubular metallic member and end seals on said member, electrode means in said envelope and supported on said end seals, means on said envelope forming a shield spaced from and having an opening opposite said electrode means, and a shutter on the side of said shield remote from said electrode means and movable with respect to the shield to present remote portions of the shutter at said opening, said shutter comprising material substantially transparent to X-rays and having an edge portion extending adjacent one of said end seals, and means on said edge in position to be influenced by forces applied through said end seal for moving said shutter.
